STOVE.

1,105,856.

Specification of Letters Patent.

Patented Aug. 4, 1914.

Application filed February 6, 1913. Serial No. 746,525.

To all whom it may concern:

Be it known that I, STEPHEN P. SMITH, a citizen of the United States, residing at Berkeley, in the county of Alameda and State of California, have invented certain new and useful Improvements in Stoves, of which the following is a specification.

My invention relates to the class of stoves especially designed for use as heaters.

10 The object of my invention is to provide a simple and economical stove adapted for using gaseous or liquid fuel, said stove being so constructed as to present a long and tortuous course for the heated products of combustion and a widely extended heating surface exposed to the room, and said stove being so connected as to draw wholly from the exterior the air necessary for the burner flame directly, and to support combustion 15 generally, and also to take from the exterior, if desired, fresh air to be heated.

To this end my invention consists in the novel stove, its construction and connections, which I shall now fully describe by 20 reference to the accompanying drawings in which—

Figure 1 is a front elevation of my stove. Fig. 2 is a vertical section on the line $x-x$ of Fig. 1. Fig. 3 is a small detail sectional view, reduced, on the line $y-y$ of Fig. 1.

The stove is formed of a shell 1 composed of suitable plates or sheets, supported on legs 2. In the lower portion of the shell is formed the combustion chamber 3, with a 35 sloping upper wall 4. The chamber 3 at its highest point communicates through a channel 5, with the first flue 6 of a vertical zig-zag series of flues 7, 8 and 9, successively communicating through end passages 10, 11 and 12. The uppermost flue 9 of the zig-zag series communicates through a passage 13 with the top heating chamber 14, which chamber communicates with the discharge flue 15 which may be supposed to extend 40 through the wall of the room or building to the exterior air or into a suitable chimney.

By referring to Fig. 2, it will be seen that between the upper wall of the flue 6 and the floor of the flue 7 the intervening heating space 16 is open through the front of the stove and is exposed to the room. In the same manner the heating space 17 between the upper wall of the flue 8 and the floor of the flue 9 is open to the room.

Across the back of the shell is a fresh air 55 flue 18, Fig. 2. From this flue 18 short nipples 19 lead into the back ends of the heating spaces 16 and 17; and said flue also communicates through openings 20 with the heating spaces 21, 22 and 23, lying between 60 the zigzag flues and between them and the combustion chamber 3, and the top chamber 14. Short nipples 24 effect communication from the front ends of the spaces 21, 22 and 23, through the front of the shell into the 65 room.

25 is a fresh air pipe which leads in from the exterior air. This pipe communicates through a branch 25' with the fresh air flue 18, said communication being controlled by 70 a damper or valve 26, seen in Figs. 2 and 3. The damper 26 also controls an opening 26' by which the flue 18 communicates with the room. The fresh air pipe 25 extends along one side of the shell 1 to about midway of 75 said side and there is enlarged vertically, the upper portion of the enlargement receiving the gas pipe 27 which passes through it and extends into the end of the burner pipe 28 which lies within the lower part of the combustion chamber 3. This burner pipe is the ordinary pipe, perforated as seen in Fig. 3, of a Bunsen burner, and the necessary air is furnished it from the upper portion of the enlarged end of the fresh air pipe 25 through 80 the apertured hood 29. The lower portion of the enlarged end of the fresh air pipe 25 connects with a branch pipe 30, which, as seen in Fig. 1, extends under the shell from side to side and this branch pipe opens upward directly into the combustion chamber 3, as seen in Fig. 3.

The operation of the stove is as follows:— Heat is supplied by the burner 28, the oxygen for the flame being furnished 95 through the apertured hood 29 from the fresh air pipe 25; and said pipe also furnishes the air necessary to support general combustion, through the branch pipe 30. All this air being from without, the air of 100 the room is not consumed. By reason of the tortuous course of the products of combustion through the several flues of the stove, the walls of the shell are well heated; and by reason of the large area of these walls, a 105 very expansive heating surface is provided to warm the air in the room. Moreover, if fresh outside air be desired, it can be drawn

in by opening the damper 26. This air will pass into the back flue 18 and thence, through the back nipples 19 and through the openings 20 and the front nipples 24 and will 5 find its way into the room, being brought into contact, during this course, with the extensive heating surfaces of the stove. When the damper 26 is closed to the fresh air pipe 25, the back flue 18 will be open to the room 10 through the opening 26', and the circulation above mentioned will be of air in the room. In Fig. 2, I show short flanges 31 depending into two of the zigzag flues. These serve to partially trap and retain the heated gases to 15 increase their effect. For the same purpose, I show the discharge flue 15 slightly dropped below the roof of the top chamber 14.

I claim:—

20 A stove comprising a casing, a combustion chamber arranged at the base of said casing, a flue disposed vertically of the casing at the rear thereof and connected with a fresh air inlet, a heating chamber disposed above the combustion chamber, said heating 25 chamber being spaced from the front wall of

the casing, said heating chamber being of greater width at the rear of the casing adjacent the flue than at its end adjacent the front of the casing, the more extensive end of the chamber abutting the flue and communicating with the same through a relatively small opening at the base of the chamber, heating chambers arranged above the first mentioned chamber, said chambers tapering in width from the rear to the front of 30 the casing their smaller ends being disposed adjacent the flue and communicating therewith through relatively small openings, the larger ends of said chambers opening through the front wall of the casing, and a 35 plurality of zigzag flues disposed intermediate the heating chambers and communicating with a stack at the top of the casing.

In testimony whereof I have signed my name to this specification in the presence of 40 two subscribing witnesses.

STEPHEN P. SMITH.
